UNITED STATES PATENT OFFICE.

SIMON JANKOWSKY, OF TULSA, OKLAHOMA.

INTERCHANGEABLE SUPPORTING STRUCTURE.

Application filed April 6, 1925. Serial No. 21,059.

To all whom it may concern:

Be it known that I, SIMON JANKOWSKY, a citizen of the United States of America, and a resident of Tulsa, Oklahoma, have 5 invented a certain new and useful Improvement in Interchangeable Supporting Structures, of which the following is a specification.

This invention relates to improvements in 10 interchangeable supporting structures, and more particularly to interchangeable supporting fixtures for use in window display devices or the like, although the invention may be applied to other uses, as will hereinafter appear.

The principal object of the invention is to provide a simple and convenient system of interlocking and interchanging structure members which are capable of being combined in a wide variety of relative positions, as for instance, in display fixtures for use in show cases or windows, in which relatively light but substantial supporting structures are desired, but which are capable of 25 being readily re-arranged in various forms and combinations to suit a wide variety of uses. More specifically, my improved system contemplates the provision of a plurality of metal pieces of substantially uniform 30 thickness throughout their length and having interchangeable connection with each other. The connections are made by the mutual engagement of slots formed in the pieces, each of said pieces being provided 35 with a plurality of slots arranged in various positions and at various angles thereon. In carrying out my invention I provide a master supporting piece having suitable means for attachment to a base, and one or 40 more pieces adapted to be attached to said master piece to project laterally therefrom at varying angles. Auxiliary pieces may 45 also be provided for attachment to the projecting pieces. I also provide connecting devices suitable for securing a shelf, such as a plate glass display rack, on the supporting structure formed of the pieces as above described.

The invention may best be understood 50 by reference to the accompanying drawings illustrating certain forms in which it may be embodied. In the drawings,

Figure 1 is a view showing one form in which my invention may be embodied, in 55 which a master supporting piece is connected to the wall and a laterally project-

ing piece is shown as connectible thereto at varying angles.

Figure 2 is a view showing a somewhat shorter master piece and illustrating the use 60 of a laterally projecting piece for the purpose of supporting a shelf such as may be used in a show-case display rack.

Figure 3 is a sectional view of a supporting structure similar to Figure 2 but utilizing 65 a different form of clamping means to secure the shelf upon the support.

Figure 4 is another form of my invention as applied to a display device used in 70 the corner of a plate glass window.

Figure 5 is a modified form somewhat similar to that shown in Figure 4 but with 75 a projecting member shown in an inclined position upon the master supporting piece.

Figure 6 is another modified form of my 75 invention in which the master supporting piece is arranged in a vertical and the laterally supporting piece is especially adapted 80 for supporting a plate glass shelf at varying angles with respect to the master supporting piece.

Figure 7 shows my invention as utilized 85 in various manners to a vertically extending cylindrical master supporting piece, and

Figure 8 shows another form of cylindrical 85 supporting piece which is rotatably mounted on a vertically extending piece.

Referring now to details shown in the drawings, Figure 1 shows one form of the invention in which a master supporting 90 piece 10 comprises a piece of flat bar material having the end portions 11-11 offset from the central part 12 and secured to a base 13 by suitable means, such as screws 14-14. Associated with this piece are one or more projecting pieces 15-15 made of bar stock of substantially the same cross sectional dimensions as the master piece 10 and connectible to the latter by double slot 95 connections of a special form. For example, the master piece 10 is provided with a vertically extending slot 18, a pair of horizontally extending slots 19-19 and inclined slots 20, 21, 22 and 23. All of these slots are of the same width as the associated 100 projecting pieces 15-15.

Referring now to the projecting pieces, it will be seen that they are also provided 105 with a plurality of slots, in the form shown having an upright slot 25 at one end thereof and inclined slot 26 at the other end thereof. Intermediate slots of similar size

may be provided, as for instance, inclined slots 27, 28 and a centrally disposed vertical slot 29. All of the slots on the projecting piece 15 are adapted to form a close fitting connection with any one of the cooperating slots on the master piece 10 above described, so that the projecting piece 15 may be arranged in a large variety of positions limited only by the number and arrangement of the 10 slots on the respective pieces. Furthermore, it will be understood that auxiliary pieces may be connected in turn to the projecting members 15, as for instance, in the slots 28 or 29, thus making it possible to form a wide 15 variety of display structures depending upon the particular requirements of the trimmer. By providing a plurality of pieces 15—15 of varying lengths and provided with connecting slots at various angles, it 20 will be understood that practically an infinite number of combinations may be constructed and in all cases a firm support is provided by reason of the close fitting engagement of the double slot connections so 25 as to eliminate the necessity of any auxiliary supporting connections besides the master supporting piece 10.

Figure 2 shows a simpler form of master piece 30 in which only three supporting 30 slots 31, 32 and 33 are formed, together with a relatively simple projecting piece 35 having only one vertically extending slot 36 at one end and an inclined slot 37 at the other end. In this form the projecting piece 35 is shown as connected in horizontal 35 position to support a shelf 39. A supporting clamp 40 is here provided for the purpose of securing the edge of the shelf 39, this clamp being formed of a piece of spring 40 metal having one end 41 of sufficient thickness to fit in the slot 37, the entire clamp being curved upwardly and extending over the top of the shelf 39 to secure the same under tension. Obviously a plurality of 45 such clamps having varying shapes as required to suit the particular position of the slot 37 may be provided. For instance, as shown in Figure 3 another form of clamp 40^a is provided consisting of a substantially 50 L-shaped piece of which the lower part 41^a fits in a vertically disposed slot 37^a opening upwardly adjacent the edge of the shelf 39^a. In still another form of retaining clamp shown in Figure 4, the clamp 40^b 55 is adapted to have a vertically extending portion 41^b fitting in a vertical slot 37^b on the underside of the supporting piece 15.

Figures 4 and 5 show a further modified 60 form of master supporting member 44 adapted to be connected to a clamp 45 for attachment to a tension screw 46 of a sheet metal window frame member 47 of any suitable form. The master piece 44 in this instance is substantially curved and provided 65 at opposite ends with slots 48—48 fitting

in slots 49—49 formed in the ends of arms 50—50 integral with the clamp 45. The master support 44 in this instance also is provided with a plurality of slots along its upper edge for engagement by laterally 70 extending pieces 15—15. In Figure 4 I show an auxiliary cross piece 55 connected by double slot connection of the necessary form intermediate the ends of the piece 15, the ends of the piece 55 herein being provided with clamps 40^a—40^a similar to the form of securing clamp shown in Figure 3 for the purpose of securing a shelf 56. In the form shown in Figure 5 the supporting piece 15 is shown reversed end to end and 80 connected to the master piece 44 at an inclined angle so as to be used for exhibiting dry goods, such as ties, which are draped over the arms of the cross piece 55 as shown.

Figure 6 shows another form of master 85 piece 60 which may be somewhat similar to the piece 10 shown in Figure 1 but secured in a vertical position. The projecting piece 61 herein shown is of a special form having a recessed upper edge adapted for fitting engagement with a shelf 62 secured between the shoulders 63—63 of the piece 61 and other shoulders 64—64 of a connecting cross member 65. The position of this projecting piece 61 may obviously be rearranged at varying angles as desired, and furthermore it may be turned end to end so that the inclined slot 66 is engaged with the master piece 60 instead of the upright slot 67 as indicated in broken lines at the 100 lower part of this figure.

Figure 7 shows another form of master supporting piece which may be utilized in connection with the projecting piece 15—15 of the general form already described. In 105 this instance it will be observed that the members 15—15 may be connected at their ends in the slots 70—70 formed at the upper periphery of the cylindrical supporting member 71 and may also be supported at 110 an angle thereto by using an inclined slot such as an intermediate slot 72, in which case the member 15 will assume the position indicated in dotted lines in this figure.

Figure 8 illustrates another modification 115 of master piece 80 which may consist of an annular member 81 provided with a plurality of slots 82—82 and having a downwardly projecting hub 83 rotatably mounted in a socket 84 at the upper end of the support 85.

In all of the forms shown it will be seen 120 that the same general type of structural pieces are provided, having uniform cross sectional area and provided with uniform slots for interchangeable connection with each other. Furthermore, a master supporting piece is provided for connection to a base, and one or more projecting pieces may be connected thereto in varying angles, and may also be reversible end to end, or 130

in the forms shown in Figures 7 and 8, the projecting pieces may be connected to the master piece adjacent their center, if desired. Means are also provided in all forms 5 for securing shelves or similar structural members at the free ends of the pieces by utilization of spring clamps fitting in the connecting slots.

While I have shown and described certain 10 forms and specific uses of my invention, it will be obvious that many other forms and uses thereof will be manifest to those skilled in the art and without departing from the scope of the invention, and therefore I do 15 not wish to be understood as limiting myself to the forms or uses shown and described, excepting as defined in the appended claims.

I claim as my invention:

- 20 1. In an interchangeable structure system, a plurality of separate supporting pieces comprising a master piece and one or more associated pieces, all being of substantially uniform cross-sectional area and provided 25 with a plurality of uniform slots arranged at varying angles to afford mutually interchangeable double slotted connection of the pieces at varying angles with respect to each other, and clamping means for securing 30 other structural parts to said pieces comprising spring clamping members having one end adapted to fit in said slots and extend into tensional engagement with said structural parts.
- 35 2. In an interchangeable structure system, a plurality of supporting pieces comprising a master piece and one or more associated pieces, all being of substantially uniform cross-sectional area and provided with a 40 plurality of uniform slots arranged at varying angles to afford interchangeable double slotted connection of the pieces at varying

angles with respect to each other, and clamping means for securing other structural parts to said pieces, comprising a series of 45 spring clamping members having one end adapted to fit in said slots and extending at angles varying with the angles of said slots.

3. In an interchangeable structure system, a plurality of supporting pieces comprising 50 a master piece and one or more associated pieces, all being of substantially uniform cross-sectional area, said associated pieces having slots adjacent opposite ends arranged at varying angles to the side edge thereof, 55 whereby said pieces are reversible end to end to afford interchangeable connection with said master piece at varying angles of incidence, and clamping means for securing other structural parts to said pieces, comprising spring clamping members having one end adapted to fit in said slots and extend into tensional engagement with said structural parts.

4. In an interchangeable structure system, 65 a plurality of supporting pieces comprising a master piece and one or more associated pieces, all being of substantially uniform cross-sectional area, said associated pieces having slots adjacent opposite ends arranged at varying angles to the side edge thereof, 70 whereby said pieces are reversible end to end to afford interchangeable connection with said master piece at varying angles of incidence, and clamping means for securing other structural parts to said pieces, comprising a series of 75 spring clamping members having one end adapted to fit in said slots and extending at right angles varying with the angles of said slots.

Signed at Tulsa, Okla., this 23rd day of March, 1925.

SIMON JANKOWSKY.
